UNITED STATES PATENT OFFICE.

FREDERICK CRAIB, OF MARTINEZ, CALIFORNIA.

DESIGN FOR AN ELECTRIC WALL BRACKET.

Application filed November 7, 1928. Serial No. 28,789. Term of patent 3½ years.

To all whom it may concern:

Be it known that I, FREDERICK CRAIB, a citizen of the United States, residing in the city of Martinez, county of Contra Costa, and State of California, have invented a new, original, and ornamental Design for an Electric Wall Bracket, of which the following is a specification, reference being had to the accompanying drawing, forming a part thereof.

The figure is a front elevation of a wall

bracket showing my new design. Only one of the lamp arms is shown completed, it being understood that the arm indicated in dotted lines is completed in the same manner as the other arm member.

I claim:

The ornamental design for an electric wall-bracket as shown.

FREDERICK CRAIB.
